UNITED STATES PATENT OFFICE.

WILLIAM F. ANKLAM, OF DETROIT, MICHIGAN, ASSIGNOR TO C. M. HALL LAMP COMPANY, OF DETROIT, MICHIGAN, A CORPORATION OF MICHIGAN.

DESIGN FOR A LAMP-FRONT FRAME.

54,823.

Specification for Design.

Patented Apr. 13, 1920.

Application filed June 15, 1918. Serial No. 240,243. Term of patent 7 years.

To all whom it may concern:

Be it known that I, WILLIAM F. ANKLAM, a citizen of the United States of America, residing at Detroit, in the county of Wayne and State of Michigan, have invented a certain new, original, and ornamental Design for Lamp-Front Frames, of which the following is a specification, reference being had therein to the accompanying drawings, in which—

Fig. 2 is a view of said frame in side elevation.

I claim:

The ornamental design for a lamp front frame, substantially as shown.

WILLIAM F. ANKLAM.
